Primary Examiner — Lilyana Bekic*(74) Attorney, Agent, or Firm* — Knobbe Martens Olson & Bear LLP(57) **CLAIM**

The ornamental design for a seal for a patient interface, as shown and described.

DESCRIPTION

FIG. 1 is a front perspective view of a seal for a patient interface;

FIG. 2 is a rear perspective view thereof;

FIG. 3 is a front elevational view thereof;

FIG. 4 is a rear elevational view thereof;

FIG. 5 is a left side elevational view thereof, the right side elevational view being a mirror image of the view of FIG. 5;

FIG. 6 is a bottom elevational view thereof; and,

FIG. 7 is a top elevational view thereof.
